UNITED STATES PATENT OFFICE

HENRY W. FISHEL, OF NEW YORK, N. Y.

DESIGN FOR A BRACELET.

SPECIFICATION forming part of Design No. 20,298, dated November 11, 1890.

Application filed October 7, 1890. Serial No. 367,376. Term of patent 7 years.

To all whom it may concern:

Be it known that I, HENRY W. FISHEL, a citizen of the United States, residing in New York city, in the county and State of New York, have invented and produced a new and original Design for Bracelets, of which the following is a specification, reference being had to the accompanying drawing, forming a part thereof, in which the figure is a perspective view of a bracelet showing my design.

The leading feature of my design for bracelet-bands consists in a watch-like figure from which the lines of the band depart at each side, intersecting at intervals and presenting the appearance of basket-work. The band-like figure A is circular in its general contour, the scalloped edges a and the curved parallel lines a' bisecting each other at a² of which give it the appearance of a three-strand braid, the ends of which terminate in a rectangular figure B, the lines b b' and bead-like figure b² of which give it the appearance of a clasp. Oppositely of the figure B, surmounting or imposed upon the band-like figure A, is the watch-like figure C, having the circular base-

lines c, surmounted by the wreath-like figure c', the irregular marginal lines of which fall within the lines c, and which wreath-like figure incloses the concentric circular lines c², within which appear a series c³ of Roman numerals and the radial lines c⁴, simulating the hands of a time-piece, giving the inclosed circular field the appearance of a watch-face. At one side of the base-lines c² is the stem-like figure c⁵. On opposite sides of the base-lines c, and imposed upon the band-like figure A, are the shell-like figures D, having the straight side lines d and scalloped marginal lines d', and also the curved diverging lines d², giving the shells the appearance of 40 being engraved.

In carrying out my design the figures comprising it may be colored to suit the taste.

I claim—

The design for a bracelet herein shown and described.

HENRY W. FISHEL.
